RAIL ANCHOR

James M. Fair, Pittsburgh, Pa.

Application January 26, 1938, Serial No. 186,925

11 Claims. (Cl. 238—327)

This invention relates to improvements in rail anchors adapted to be applied to railroad rails to engage cross ties or other stationary parts of the road bed to prevent longitudinal displacement or creeping of the rails over the supports therefor.

The particular type of anchor to which the invention relates is formed of a steel bar and comprises a bottom bar adapted to extend transversely beneath a rail base and to engage the bottom thereof, an arm extending upwardly from one end of the bottom bar and adapted to extend inwardly over one side of the rail base and to have its free end portion engaged with the top of the rail base, and means on the other end of the bottom bar to retain the anchor in place upon the rail base.

Rail anchors of this particular type, in the various forms in which they have been used, have been defective and objectionable in cases of derailed car wheels, because, when the parts or arms of the anchors which extend over and engage the top of a rail base have been struck by derailed wheels, the result has been that the blows struck by such wheels have been applied to the anchors with sufficient force to cause them to break parts of the rail bases in the regions of their engagement therewith, or otherwise to impair or damage the same to such an extent as to make it necessary to remove the damaged rails from the track and to substitute new rails for them.

The primary object of the invention is to provide a rail anchor of such novel and advantageous construction that the danger of rail breakage and damage, under the conditions referred to, will be materially lessened, and, in many cases, completely eliminated.

A further object of the invention is to so form and relate the parts of the improved anchor as to increase the strength and holding power thereof without increasing the quantity of metal employed in the construction thereof.

The invention resides in the novel construction, combination and arrangement of the parts of the improved anchor, and in the relation thereof to the railroad rail to which it is applied, as will be hereinafter described and claimed.

In the accompanying drawing, illustrating the invention,

Figure 1 is a plan of a part of a railroad rail, a part of a cross tie supporting the same, and the improved rail anchor applied to the rail,

Figure 2 is a side view thereof,

Figure 3 is a vertical section, on line 3—3 of Fig. 1, and

Figures 4, 5, 6 and 7 are sectional details, on lines 4—4, 5—5, 6—6 and 7—7, respectively of Fig. 3.

Referring to the drawing, 2 designates a railroad rail, and 8 an underlying cross tie forming

a part of the road bed, and supporting the rail 2, and over which the rail tends to creep forwardly or in the direction of the arrows in Figs. 1 and 2, under the well known conditions.

The improved rail anchor 9 is applied to the base 10 of the rail 2, and it is formed of a single piece of bar of steel or other suitable metal, and it comprises a bottom bar 11 extending transversely beneath the rail base 10, an arm 12 extending upwardly from one end of the bar 11 and inwardly over one side of the rail base 10, and a projection 13 on the other end of the bar 11 and extending upwardly therefrom above the bottom of the rail base adjacent to the other side thereof.

The central portion of the bottom bar 11 is downwardly bowed, as illustrated, and it has two bearing parts or surfaces 14 and 15 which engage the bottom surface of the rail base adjacent to the respective sides thereof.

The arm 12 is bowed outwardly and upwardly in spaced relation to the adjacent side edge of the rail base 10 as the arm extends from the bottom bar 11; and the arm 12 extends inwardly over the adjacent side of the rail base 10, and it terminates in a free end portion 16 having a bottom bearing surface 17 which engages the top surface of the rail base, as shown in Fig. 3 of the drawing.

When the anchor is applied to the rail, the projection 13 rests adjacent and in close proximity to the adjacent side edge of the rail base, and it serves to prevent accidental displacement of the anchor outwardly from the opposite side of the rail base.

In the normal condition of the rail anchor, before being applied to the rail base, the space between its bearing surfaces 14 and 17 is somewhat less than that shown in the drawing, and the relation of its bearing surfaces 14, 15 and 17 are such that when the anchor is applied to the rail base 10, the bar 11 and arm 12 are sprung apart, so that the anchor, in tending to resume its normal condition, will press the bearing surfaces 14 and 15 of the bar 11 up against the bottom of the rail base, and will press the bearing surface 17 of the arm 12 down upon the top of the rail base by the resilient action of the metal forming the anchor, and thereby cause the anchor to firmly grip the rail base.

In applying the anchor to the rail base, the bar 11 is extended beneath the rail base, and the arm 12 is extended over one side of the rail base until the top of the projection 13 and the bearing surface 14 engage the bottom of the rail base, and the bearing surface 17 engages the top of the rail base. The anchor is then driven onto the rail base in the direction of the arrow in Fig. 3 until the projection 13 clears the adjacent side edge of the rail base and is snapped up into the

position shown in Fig. 3. As the anchor is thus applied to the rail base the arm 12 and that part of the bar 11 beneath it are sprung apart, and thereafter, in the final, applied position of the anchor, the arm 12 and bar 11 grip the rail base 10 firmly between them, as the anchor tends to resume its normal condition.

The anchor is applied to the rail base 10 adjacent to a cross tie 8, as shown in Figs. 1, 2 and 3, and, thereafter, as the rail tends to creep forwardly or in the direction of the arrows in Figs. 1 and 2, the bar 11 will engage the cross tie 8 and prevent the creeping of the rail, due to the gripping action of the bar 11 and arm 12 of the anchor upon the rail base.

The improved rail anchor is constructed of a single piece or bar of steel of substantially triangular cross section which is suitably bent and pressed to form the parts of the anchor as illustrated in the drawing.

The three sides of the triangular bar from which the anchor is made extend continuously through the bottom bar 11 of the anchor and through the arm 12 thereof, and one of the 25 three sides 18 constitutes the top surface of the bottom bar 11 and the bottom surface of the arm 12; another of the three sides 19 constitutes the forward surface of the bottom bar 11 and the forward surface of the arm 12; and another 30 of the three sides 20 constitutes the bottom and rearward surface of the bar 11 and the top and rearward surface of the arm 12.

By making the side 18 of the triangular bar of which the anchor is formed narrower than its 35 other sides 19 and 20, I am enabled to increase the dimensions of the bar 11 and arm 12 which extend transversely of or at right angles to the rail 2 with relation to the dimensions thereof which extend longitudinally of the rail and thereby increase the strength and holding power 40 of anchors of this type without increasing the quantity of metal used in the manufacture thereof.

The forward surface 19 of the bar 11 extends 45 at right angles to the bottom of the rail base 10 for engagement with the cross tie 8 and the top surface 18 of the bar 11 extends at right angles to the surface 19 to provide the bearing parts or surfaces 14 and 15 for the bar 11.

That portion of the arm 12 which extends inwardly toward and over the adjacent side of the rail base 10 is formed so that the upper portion 50 of the arm will extend forwardly and upwardly from the lower portion thereof and overhang a free space between it and the top of the rail base, and so that the arm 12 will have a part 16 engaged with the rail base at the free end portion of the arm, and another part 21 spaced above the top of the rail base 10.

The forward surface 19 of the arm 12 extends 60 forwardly and upwardly from the forward side of bottom surface 18 of the arm, and it is connected thereto by a curved portion 22 which constitutes a rounded bearing on which the arm 12 may be tilted laterally on the underlying rail base 10.

It will now be understood that if a car wheel, moving forwardly on the rail 2, becomes derailed and strikes the rail anchor arm 12, the 70 impact of the derailed wheel will be upon the forwardly and upwardly inclined arm 12 in the region, indicated at 23, above the part 21, of the arm which is spaced above the rail base 10. When the arm 12 is thus struck by a derailed wheel, the force of the blow will not only bend

the arm 12 to lessen or close the space 24 between the arm and the rail base, but it will also force the rounded bearing surface 22 down upon the rail base and tilt the arm forwardly on such rounded surface with the result that the blow delivered by the wheel to the anchor will be so cushioned by the action of the arm that the danger of rail breakage and damage, heretofore present, will be greatly reduced, and in many cases completely eliminated.

The provision of the rounded bearing surface 22 for the arm 12 lessens or eliminates the danger of damage to the rail heretofore caused by the objectionable nicking of the rail base by corner portions of rail anchors of prior construction.

In some instances, the lateral tilting of the rail anchor arm 12, by a derailed wheel will have the effect of twisting the anchor off from the rail base and thus prevent damage to the rail.

I claim:

1. The combination with a railroad rail, of a rail anchor comprising a bar extending transversely beneath the rail base and engaged with the bottom thereof, an arm extending upwardly from one end of the bar and inwardly over one side of the rail base and having its free end portion engaged with the top of the rail base, the upper portion of said arm extending laterally of the body of the arm and forwardly from the forward surface of the lower portion of said arm, and the forward part of said arm extending upwardly to a greater height above the rail base than the height to which the rearward part of said arm extends, and a projection on the other end of the bar extending above the bottom of the rail base adjacent to the edge of the other side thereof.

2. The combination with a railroad rail, of a rail anchor comprising a bar extending transversely beneath the rail base and engaged with the bottom thereof, an arm extending upwardly from one end of the bar and inwardly over one side of the rail base and having its free end portion engaged with the top of the rail base, the upper part of said arm extending laterally of the body of the arm and forwardly from the forward surface of the lower part thereof in spaced relation to the top of the rail base, and the top surface of said arm progressively rising from the rearward side of the arm to the forward side thereof, and a projection on the other end of the bar extending above the bottom of the rail base adjacent to the edge of the other side thereof.

3. The combination with a railroad rail, of a rail anchor comprising a bar extending transversely beneath the rail base and engaged with the bottom thereof, an arm extending upwardly from one end of the bar and inwardly over one side of the rail base and having a part thereof engaged with the top of the rail base at the free end portion of the arm and another part thereof spaced above the top of the rail base, the upper part of the spaced portion of said arm extending laterally of the body of the arm and forwardly from the forward surface of the lower part of the spaced portion of said arm, and the forward part of the spaced portion of said arm extending upwardly to a greater height above the rail base than the height to which the rearward part of the spaced portion of said arm extends, and a projection on the other end of the bar extending above the bottom of the rail base adjacent to the edge of the other side thereof.

4. The combination with a railroad rail, of a rail anchor comprising a bar extending transversely beneath the rail base and engaged with the bottom thereof, an arm extending upwardly from one end of the bar and inwardly over one side of the rail base and having a part thereof engaged with the top of the rail base at the free end portion of the arm and another part thereof spaced above the top of the rail base, the upper part of the spaced portion of said arm extending laterally of the body of the arm and forwardly from the forward surface of the lower part of the spaced portion of said arm, and the top surface of the spaced portion of said arm progressively rising from the rearward side of the arm to the forward side thereof, and a projection on the other end of the bar extending above the bottom of the rail base adjacent to the edge of the other side thereof.
- 20 5. The combination with a railroad rail, of a rail anchor comprising a bar extending transversely beneath the rail base and engaged with the bottom thereof, an arm extending upwardly from one end of the bar and inwardly over one side of the rail base, and a projection on the other end of the bar extending above the bottom of the rail base adjacent to the edge of the other side thereof; said arm being of substantially triangular cross section providing a bottom surface, a top surface and a forward surface for the arm, said bottom surface having a part thereof engaged with the top surface of the rail base at the free end portion of the arm and another part thereof spaced above the top of the rail base, said top surface extending forwardly and upwardly from the region of the rearward side of the spaced portion of said bottom surface, and said forward surface extending forwardly and upwardly from the region of the forward side of the spaced portion of said bottom surface.
- 30 6. The combination with a railroad rail, of a rail anchor comprising a bar extending transversely beneath the rail base and engaged with the bottom thereof, an arm extending upwardly from one end of the bar and inwardly over one side of the rail base and having its free end portion engaged with the top of the rail base, and a projection on the other end of the bar extending above the bottom of the rail base adjacent to the edge of the other side thereof; said bar and said arm being of substantially triangular cross section providing three sides extending continuously throughout the same, one of said sides constituting the forward surface of the bar and the forward surface of the arm, the forward surface of the bar extending substantially at right angles to the rail base for engagement with a cross tie, and the forward surface of said arm extending upwardly and forwardly from a position above the rail base.
- 40 7. A rail anchor comprising a bottom bar adapted to extend transversely beneath a rail base, an arm adapted to extend upwardly from one end of the bar and inwardly over one side of the rail base, and means on the other end of the bar to retain the anchor in place upon the rail base, said anchor being formed of a bar of substantially triangular cross section having a part of one of its three sides constituting the top surface of said bottom bar adapted to engage the bottom of the rail base and another part of the same side constituting the bottom surface of said arm adapted to engage the top of the rail base; the forward surface of said arm extending forwardly and upwardly from the forward side of the bottom surface of the arm, and the top surface of said arm extending forwardly and upwardly from the rearward side of the bottom surface of the arm.
- 50 8. A rail anchor comprising a bottom bar adapted to extend transversely beneath a rail base, an arm adapted to extend upwardly from one end of the bar and inwardly over one side of the rail base, and means on the other end of the bar to retain the anchor in place upon the rail base, said anchor being formed of a bar of substantially triangular cross section having a part of one of its three sides constituting the top surface of said bottom bar adapted to engage the bottom of the rail base and another part of the same side constituting the bottom surface of said arm adapted to engage the top of the rail base, the forward surface of said arm extending forwardly and upwardly from the forward side of the bottom surface of the arm, the top surface of said arm extending forwardly and upwardly from the rearward side of the bottom surface of the arm, and the forward surface of said bottom bar extending downwardly from the top surface thereof substantially at right angles thereto for engagement with a cross tie.
- 60 9. A rail anchor comprising a bottom bar adapted to extend transversely beneath a rail base, an arm adapted to extend upwardly from one end of the bar and inwardly over one side of the rail base, and means on the other end of the bar to retain the anchor in place upon the rail base, said arm having a forward surface extending forwardly and upwardly from the forward side of the bottom surface of said arm in a direction laterally of the arm, and said arm having a top surface extending forwardly and upwardly from the rearward side of the bottom surface of the arm.
- 70 10. A rail anchor comprising a bottom bar adapted to extend transversely beneath a rail base, an arm adapted to extend upwardly from one end of the bar and inwardly over one side of the rail base, and means on the other end of the bar to retain the anchor in place upon the rail base, said arm having a forward surface extending forwardly and upwardly from the forward side of the bottom surface of the arm in a direction laterally of the arm and being connected thereto by a curved portion constituting a rounded bearing on which the arm may be tilted laterally on a rail base, and said arm having a top surface extending forwardly and upwardly from the rearward side of the bottom surface of the arm.
11. A rail anchor formed of metal and comprising a bottom bar adapted to extend transversely beneath the rail base, and an arm adapted to extend upwardly from one end of the bar and inwardly over one side of the rail base to clamp the rail base between the bar and the arm, said arm having a flat bottom surface adapted to engage the top surface of the rail base, and said arm having an upper portion extending longitudinally of the arm and being of less width than the lower portion thereof and whose top part is spaced forwardly from the forward side of said bottom surface, the major portion of the metal forming the arm being located rearwardly of the forward side of said bottom surface.

JAMES M. FAIR.
